UNITED STATES PATENT OFFICE.

HARRY F. ROACH, OF ST. LOUIS, MISSOURI.

RAIL-JOINT.

1,258,249.

Specification of Letters Patent.

Patented Mar. 5, 1918.

Application filed June 23, 1916. Serial No. 105,349.

To all whom it may concern:

Be it known that I, HARRY F. ROACH, a citizen of the United States, residing at St. Louis, Missouri, have invented a certain 5 new and useful Improvement in Rail-Joints, of which the following is a full, clear, and exact description, such as will enable others skilled in the art to which it appertains to make and use the same.

10 This invention relates to rail joints of the type that comprises angle bars, fish plates or similar splice members arranged on opposite sides of the webs of the abutting rails in engagement with the base flanges and the 15 heads of the rails.

One objectionable feature of prior rail joints of the general type mentioned, namely rail joints constructed on the splice theory, is that they form "hard spots" or 20 short sections in the track that are much stiffer than the sections of the track that extend between the rail joints, this, of course, being due to the fact that the joint members are so designed that they impart considerable 25 additional stiffness to the portions of the rails they embrace. These hard spots or abnormally stiff portions of the track not only result in breakage of the rails within the rail joints or at the ends of the 30 joints, due to a heavy load passing from a portion of a rail that has a certain degree of stiffness onto a portion of the rail that is reinforced and stiffened by the joint members that engage the head and base flange 35 of same, but they also prevent the natural wave motion of the rail passing uniformly through the joints of the track, due, of course, to the variation in stiffness in the terminal portions of the rails and the intermediate 40 portions of the rails. Furthermore, this variation in stiffness above referred to causes the joint members to be subjected to vertical bending strains intermediate their ends.

45 One object of my invention is to provide a rail joint that is similar to rail joints of the general type above discussed, in that it comprises members arranged on opposite sides of the webs of the rail in engagement 50 with the heads and base flanges of the rails, but which is so constructed that the wave

motion of the rails throughout the track is continued uniformly through the joints of the track. Other objects of my invention are, to provide a rail joint of the character just referred to, which is so designed that it minimizes the vertical bending moment at the center portion of the joint to a negligible degree and causes the center portion of the joint to be brought into structural 55 shear resistance; it eliminates the tendency of the rails to break, due to excessive variations in stiffness in the terminal portions and the intermediate portions of the rails, and it overcomes the necessity of accurately 60 spacing the track ties.

To this end I have devised a rail joint, which, in its simplest form, comprises two members arranged on opposite sides of the webs of two abutting rails and provided 70 intermediate their ends with means that bears against the undersides of the heads and against the upper sides of the base flanges of the rails, the end portions of said members being spaced away from the heads 75 and from the base flanges of the rails, so as to permit the rails to move vertically at the ends of the joint under load, both upwardly and downwardly. The joint can either be positioned over a tie or between two ties 80 and when it is positioned over a tie, the rails can either be supported by an ordinary tie plate or by a tie plate of the design hereinafter described, which is so constructed 85 that it reduces the impact on the tie and also reduces the tendency of the tie to rock or roll. The joint members may be of any preferred shape in cross section and may either be cast, rolled or forged or formed by a combined rolling, bending or shaping 90 operation.

Figure 1 of the drawings is a side elevational view, partly broken away, of a rail joint constructed in accordance with my invention.

Fig. 2 is a view of said joint, partly in cross section, and partly in end elevation.

Fig. 3 is a perspective view, illustrating a modification of my invention.

Fig. 4 is a side elevational view, partly broken away, illustrating another form of my invention.

Fig. 5 is a view partly in vertical cross section and end elevation of the rail joint shown in Fig. 4.

Fig. 6 is a perspective view of the tie plate of the joint shown in Figs. 4 and 5.

Fig. 7 is a side elevational view, illustrating another form of my invention.

Fig. 8 is a horizontal sectional view of the same, taken on the line 8-8 of Fig. 7; and

Fig. 9 is a horizontal sectional view, illustrating still another form of my invention.

Referring to Fig. 1 of the drawings, A designates two members that are arranged on opposite sides of the vertical webs of two abutting rails B, and C and C' designate bolts or other suitable fastening devices that pass transversely through said members and through the webs of the rails. Each of the members A is provided intermediate its ends with means 1 and 2 that bear against the undersides of the heads 3 of the rails and against the upper sides of the base flanges 4 of the rails, respectively, said means 1 and 2 preferably consisting of integral portions on the upper and lower edges of each of the members A that extend a short distance on each side of the space between the ends of the rails. The end portions of each of the members A are spaced away from the heads and from the base flanges of the rails, as shown in Fig. 1, and the holes in the webs of the rails through which the end bolts C' pass are made slightly larger than said bolts, so as to permit the rails B to deflect slightly and also move vertically at the ends of the joint under load. By constructing the joint members in this manner I obtain practically a hinge connection between the terminals of the rails and the center portion of the joint without the use of a base plate or supporting structure under the base flanges of the rails. When the joint is in service the load imposed on one rail by a wheel traveling over the same will be transmitted to the center portion of the joint through the end of the rail, thus bringing the members A into shear resistance at the center of the joint. When the load passes from said rail onto the adjacent rail, the load will be transmitted through the end portion of the latter to the center portion of the members A in exactly the same manner just described. It will thus be seen that in a rail joint of the construction herein illustrated the vertical bending moment of the members A at the center of the joint is reduced to a negligible degree, so that it is not necessary to consider the bending moment as a factor in designing a joint for the particular work that it is required to do. The hinge connection between the rails and the joint members A eliminates hard spots in the track and prevents reverse strains from being created in the joint, as such a connection permits the

wave motion of the rails to pass through the joint uninterrupted. Furthermore, such a joint can be made as stiff as desired without danger of causing the rails to break, owing to the fact that it does not add materially to the stiffness of the portions of the rails which it embraces. My improved rail joint is not only superior to splice type rail joints in the respects previously pointed out, but it can be made much lighter without decreasing the efficiency of the joint or sacrificing strength, on account of the fact that the joint members are of such design that the center portions of the same are subjected to vertical shearing strains instead of vertical bending strains when the joint is in service. The length or area of the portions 1 and 2 of the members A can be varied, so long as the end portions of said members are spaced far enough away from the undersides of the heads of the rails and from the upper sides of the base flanges of the rails to permit the rails to move vertically at the ends of the joint, upwardly and downwardly, under load.

As previously stated, the members A may be of any preferred cross-sectional shape and may be formed in various ways without departing from the spirit of my invention. In the form of my invention illustrated in Fig. 1 of the drawings each of the members A consists of a casting, and in the form of my invention illustrated in Fig. 3 the members A each consist of a D-bar, or bar of substantially D shape in cross section, whose center portion snugly engages the heads and base flanges of the rails and whose end portions are of less depth or height than the vertical distance between the heads and base flanges of the rails, so that they will not bear against the same. In the form of my invention illustrated in Figs. 4 and 5 the members A consist of castings that are substantially angle-shaped in cross section, and in the form of my invention illustrated in Figs. 7, 8 and 9 each of the members A is formed from an angle bar of the kind now used extensively in railway track structures, but having its end portions deformed either by shearing, framing, or in any other suitable manner, so that they will not bear against the undersides of the heads and against the upper sides of the base flanges of the rails at the ends of the joint.

The joint is preferably provided with means that prevents the members A from being arranged unparallel to the rails during the operation of tightening the end bolts C' of the joint. In the form of my invention shown in Figs. 1 and 2 said means consists of lugs 6 arranged on the inner sides of said members adjacent the ends of the same and so proportioned that they will limit the inward movement of the end portions of the

members A toward the rails during the operation of tightening the bolts that secure the members A and the rails together. In the form of my invention illustrated in Fig. 3 the end portions of the members A are bent inwardly at 6^a, so that they will bear against the webs of the rails during the operation of tightening the end bolts C', and thus limit the inward movement of the end portions of the members A. A similar construction is illustrated in Fig. 9 of the drawings, which illustrates a rail joint constructed in accordance with my invention and formed from angle bars whose end portions have been deformed or shaped in the manner previously described, and in Fig. 8 of the drawings I have illustrated still another modification, wherein washers or spacing devices 6^b are arranged between the webs of the rails and the members A at the ends of the joint, so as to limit the inward movement of the end portions of the members A relatively to the rails.

By eliminating a base plate or supporting element for the base flanges of the rails, I overcome the necessity of accurately spacing the track ties, as my improved joint is just as efficient when positioned between two ties as when positioned above a tie. In cases where the joint is positioned above a tie I prefer to use a tie plate C of the construction shown in Figs. 4, 5 and 6, although it is not essential that a tie plate of this particular form be used. The tie plate shown in Figs. 4, 5 and 6 is provided intermediate its ends, preferably at approximately its center, with a flat surface 7 on which the end portions of the base flanges of the rails rest, the remaining portion 7^a of the top face of said tie plate being inclined downwardly from the rail-supporting surface 7, so as to prevent the base flanges of the rails from normally resting on the end portions of the tie plate, but still permit the rails to deflect vertically at the ends of the joint under load. A tie plate of the construction described reduces the amount of work that the joint is called upon to perform, owing to the fact that the point of revolution is a short distance from the ends of the rails; it comprises a flat supporting surface of relatively great area for the terminal portion of the rails when the wheel load is immediately over the ends of the rails, and it tends to eliminate rolling or rocking of the tie.

Having thus described my invention, what I claim, and desire to secure by Letters Patent, is—

60 1. A rail joint, comprising two members arranged on opposite sides of abutting rails and having their end portions spaced away from the heads and from the base flanges of the rails, and means arranged intermediate

the ends of each of said members that bears 65 against the undersides of the heads and against the upper sides of the base flanges of the rails.

2. A rail joint, comprising coöperating members spaced apart to receive abutting 70 rails and provided with means lying in different horizontal planes than the end portions of said members that bear against the undersides of the heads and against the upper sides of the base flanges of the rails. 75

3. A rail joint, comprising two members arranged on opposite sides of the webs of the rails and provided intermediate their ends with means that coöperates with the heads and with the base flanges of the rails to form 80 substantially a hinge connection between the rails and the center portion of the joint, said members being so formed and combined with the rails that the rails can move vertically slightly, both up and down, relatively 85 to the end portions of said members under load.

4. A rail joint, comprising two members arranged on opposite sides of the webs of the rails in engagement with the heads and 90 with the base flanges of the terminal portions of the rails, said members being so constructed and combined with the rails that the rails can move vertically both up and down relatively to said members sufficiently 95 at the ends of the joint under load to permit the wave motion of the rails to pass through the joint.

5. A rail joint, comprising two members arranged on opposite sides of the webs of the rails with their end portions spaced 100 away from the heads and the base flanges of the rails and their intermediate portions bearing against said heads and base flanges.

6. A rail joint, comprising two members 105 arranged on opposite sides of the webs of two abutting rails above the base flanges of the same and designed in such a manner that they support and connect the terminals of the rails together, but still permit the rails 110 to move vertically, both up and down, relatively to said members at the ends of the joint when the rails are under load.

7. A rail joint member adapted to be arranged on one side of abutting rails and having its end portions so formed that they do not engage the undersides of the heads and the upper sides of the base flanges of said rails at the ends of said member, and bearing portions on said member on which the 115 terminals of the rails can exert pressure when the rails are under load.

8. A rail joint, comprising two members arranged on opposite sides of the webs of abutting rails and provided with portions 120 lying above the base flanges of the rails on which the terminal portions of the rails fulcrum when said rails are under load, said

members being so designed that they do not interfere with the vertical movement of the rails, both up and down, relatively to said members at the ends of the joint when the 5 rails fulcrum on said members.

9. A rail joint, comprising members arranged on opposite sides of the webs of abutting rails and having their end portions so formed that the rails can move vertically at 10 the ends of the joint relatively to said members when said rails are under load, means on said members intermediate the ends of the same that bear against the undersides of the heads and against the upper sides of the 15 base flanges of the rails so as to support or sustain the terminal portions of the rails, and means arranged adjacent the ends of said members that are adapted to coöperate with the rails to hold said members in parallel relation to the rails when the end bolts of the joint are being tightened.

10. A rail joint, comprising members arranged on opposite sides of the webs of abutting rails and having portions that bear 25 under the heads of the rail and over the base flanges of the rail, the length of said portions being less than the distance between the end bolts of the joint.

11. A rail joint, comprising members arranged on opposite sides of the webs of abutting rails and provided intermediate their ends with portions that bear under the heads of the rails and over the flanges of the rails, the end portions of said members 35 being spaced away from said heads and flanges; and means for preventing said members from being drawn out of parallel relation with the rails by unduly tightening the end bolts of the joint.

12. A rail joint, comprising two members arranged on opposite sides of the webs of abutting rails, and a tie plate separate and distinct from said members, said members and tie plate being so constructed that the 45 rails can move vertically slightly at the ends of the joint relatively to said tie plate and relatively to said members when the rails are under load.

13. A rail joint, comprising a tie plate

provided intermediate its ends with a surface on which the terminal portions of the rails rest and having its end portions normally spaced away from the base flanges of the rails, members separate and distinct from said tie plate arranged on opposite 55 sides of the rails with their end portions spaced away from the heads and the base flanges of the rails, and bearing portions on said members intermediate the ends of the same that bear snugly against the undersides of the heads and against the upper sides of the base flanges of the rails.

14. A rail joint, comprising two members arranged on opposite sides of the webs of abutting rails and provided intermediate 65 their ends with portions that coöperate with the heads and with the base flanges of the rails to form practically hinge connections between the rails and the center portions of said members which permits the rails to 70 move slightly vertically with relation to the end portions of said members when the rails are under load, and a tie plate having no direct connection with said members and provided intermediate its ends with a flat 75 bearing surface for the base flanges of the rails and end portions that are normally spaced away from the undersides of said base flanges.

15. A rail joint, comprising two members 80 arranged on opposite sides of the webs of abutting rails and provided intermediate their ends with portions that coöperate with the heads and with the base flanges of the rails to form practically hinge connections 85 between the rails and the center portions of said members, means arranged adjacent the ends of said members that coöperate with the webs of the rails to limit the inward movement of the end portions of said members toward the rails, and a tie plate having no direct connection with said members and provided intermediate its ends with a flat bearing surface for the base flanges of the rails and end portions that are normally spaced away from the undersides of 95 said base flanges.

HARRY F. ROACH.
